JOHN A. JOHNSON, OF CRAWFORDSVILLE, INDIANA, ASSIGNOR TO JOHNSON ACETYLENE GAS COMPANY, OF CRAWFORDSVILLE, INDIANA, A CORPORATION.

VALVE-ACTUATING MECHANISM.

1,147,325.

Specification of Letters Patent. Patented July 20, 1915.

Application filed July 28, 1914. Serial No. 853,596.

To all whom it may concern:

Be it known that I, JOHN A. JOHNSON, a citizen of the United States, residing at Crawfordsville, in the county of Montgomery and State of Indiana, have invented certain new and useful Improvements in Valve-Actuating Mechanism, of which the following is a specification.

This invention relates to certain actuating mechanism for actuating that type of a valve for discharging carbid from the carbid-receptacles into the generating chambers of acetylene gas generators which contemplates the use of two valves operated by a single valve-stem in which the movement of one valve, in a given direction, is at variance with the movement of the other valve.

The object of the invention consists in the provision of a simplified construction of actuating valve mechanism for actuating a multiple of valves for controlling the discharge of carbid from carbid-receptacles into the generating chambers of acetylene gas generators.

A further object of the invention consists in the provision of a valve actuating mechanism for actuating a multiple of valves for controlling the discharge of carbid from carbid-receptacles into the generating chambers of acetylene gas generators which is cheap to manufacture, durable and efficient in its operation.

I accomplish the object of the invention by means of the construction illustrated in the accompanying drawings, forming a part hereof, in which—

Figure 1 is a central vertical section through a carbid-receptacle for temporarily storing carbid in acetylene gas generators, showing my invention in operative position. Fig. 2 is an underside plan view of the member forming the top portion of the carbid-receptacle, showing my improved valve operating mechanism in operative position, which view is on a considerably reduced scale from that shown in Fig. 1.

Referring to the drawings, the carbid-receptacle comprises a hollow metal cylinder 10, and fitted into the lower end of this cylinder is a conically-shaped bottom 11 having a discharge opening 12 at its lowest point. The upper end of the cylinder 10 is inclosed by means of a top 14 having a depending annular flange 15 which projects into the cylinder 10. The bottom 11 and

top 14 are held in position in the cylinder 10 by means of a pair of bolts 16. Access is gained to the interior of the carbid-receptacle through the openings 18 which are normally closed by the lids 19 which are hinged to the top 14.

The discharge opening 12 is normally closed by means of a valve 20 which is secured to the end of the valve-stem 21, the latter extending vertically and centrally within the interior of the carbid-receptacle. The upper end of the valve-stem 21 is threaded to receive a thumb-nut 22, and the valve-stem and valve are lifted in a vertical direction away from the discharge opening 12 by means of a pair of opposed levers 23 which engage the underside of the thumb-nut 22. The ends of the levers 23 are arranged on opposite sides of the valve-stem 21 so that the force is equally applied to the opposite sides of the thumb-nut 22 when the valve-stem 21 is to be elevated. This construction will insure uniformity of movement of raising the valve-stem in a vertical direction and will prevent binding of the parts. The levers 23 are mounted on suitable transverse shafts 24 which have bearings in the parallel ribs 26 of the top 14. The outer ends of the levers 23 engage the curved ends of a hanger 30, the latter being provided on its top and at the center with a vertical pin 31 which projects exteriorly of the carbid-receptacle through an opening 32 in the top 14.

The valve 20 is unseated when the gas has been reduced within the gas bell (not shown) to such a point where it is desirable to increase the supply of gas, and this may be accomplished by any suitable means moving with the gas bell to engage the upper end of the vertical pin 31, causing said pin to be depressed. With the downward movement of the pin 31 a like movement is imparted to the hanger 30, which movement is imparted to the outer ends of the levers 23, causing the inner ends of the levers to be elevated and carrying the valve-stem 21 and valve 20 upwardly, leaving the discharge opening 12 exposed. By means of the thumb-nut 22 lost motion between the levers 23 and valve 20 may be taken up and the amount of throw or travel accorded said valve may be regulated. Surrounding the valve 20 and the valve-stem 21, immediately above the valve 20, is a second valve 35

which is normally held into contact with the interior surface of the conical bottom 11 by gravity. This valve protects the valve 20 against any interference in its action by 5 lumps of carbid. It will be noted that the bottom of valve 35 is depressed, leaving a sharp cutting-edge around its lower end to disintegrate lumps of carbid that may engage its lower cutting-edge. By this construction 10 the valve 35 breaks the immediate lumps of carbid into minute particles, and as the valve 35 is seated in advance of the valve 20 these smaller particles of carbid beneath said valve 35 will flow out beneath 15 the oncoming end of the valve 20 through the discharge opening 12, leaving the bottom 11 beneath the valve 35 clear so as to insure proper seating of the valve 20 at all times. The act of disintegrating the lumps 20 of carbid coming into contact with the lower edge of the valve 35 is made more certain by forming the valve of iron, thus greatly increasing its weight. It will be noted that the valve 35 is seated before the valve 20 25 so that the flow of carbid is cut off and the carbid that has passed beneath the valve 35 will be discharged through the discharge opening 12 before the valve 20 is seated. When the valve-stem 21 is lifted the valve 30 20 is unseated before it engages and lifts the valve 35. To prevent the carbid within the carbid-receptacle from impinging and interfering with the vertical movement of the valves 20 and 35 and the valve-stem 21 35 they are protected by a hood 40 and a hollow tube 41 which surrounds these parts. The lower edge of the hood 40, where it con-

tacts the bottom 11, is provided with a plurality of notches 42 which form passageways for the passage of the carbid to the 40 discharge opening 12.

I claim:

1. The combination, with a carbid holding receptacle having a carbid discharge opening, of a valve for normally sealing 45 said opening, a valve-stem for moving said valve from said opening, a pair of centrally pivoted levers arranged on opposite sides of said valve-stem for applying a uniform lifting force to the latter, and a single means 50 for connecting the outer ends of said levers and for uniformly actuating said levers.

2. The combination, with a carbid holding receptacle having a discharge opening, 55 of a valve for normally sealing said opening, a valve-stem for moving said valve away from said opening, a pair of centrally pivoted levers arranged on opposite sides of said valve-stem for applying a uniform lifting force to the latter, a single means for 60 connecting the outer ends of the levers and for uniformly actuating said levers, and a nut threaded upon the upper end of said valve-stem for regulating the travel of said 65 valve.

In witness whereof, I have hereunto set my hand and seal at Crawfordsville, Indiana, this 23rd day of July, A. D. one thousand nine hundred and fourteen.

JOHN A. JOHNSON. [L.S.]
